UNITED STATES PATENT OFFICE.

ROBERT T. WILDE AND SAMUEL H. LYON, OF BROOKLYN, NEW YORK.

IMPROVEMENT IN DIES FOR FORMING HATS.

Specification forming part of Letters Patent No. 37,993, dated March 24, 1863.

To all whom it may concern:

Be it known that we, ROBERT T. WILDE and SAMUEL H. LYON, both of the city of Brooklyn, in the county of Kings and State of New York, have invented a new and useful Improvement in Dies or Blocks for Pressing and Forming Hats and other Coverings for the Head; and we do hereby declare that the following is a full, clear, and exact description of the same, reference being had to the accompanying drawings, forming part of this specification.

This invention is applicable to all dies and blocks, whether of metal or other material, on the exterior of which the bodies of hats or other coverings for the head are pressed or formed either by the use of an external die by ironing by hand or by other means. Its object is to provide for the pressing and forming of crowns of bell or other shape which renders the successful use of a solid die or block impracticable owing to the difficulty of removing the hat therefrom; and it consists in a certain construction and arrangement of a series of pieces of which the die or block is composed, and a certain mode of combining and operating the same by which the above result is obtained.

Figures 1 and 2 are central, vertical sections of die for forming a bell-crowned hat constructed according to my invention, showing it in two different conditions, the portion upon which the brim is formed being omitted as unnecessary for the illustration of my invention. Fig. 3 is a view of the under side of the same. Fig. 4 is a top view of the same with the top plate removed to expose the interior.

Similar letters of reference indicate corresponding parts in the several figures.

The lower portion, A, of the die is made of one piece of a form corresponding with that intended for the lower portion of the hat, and in this piece there is an opening, *a a*, across which a stout bar, B, is firmly secured by screws *b b*. The top piece, C, consists of a plate of a form corresponding with that of the top of the crown, but no larger in any direction than the lower part of the piece A, so that it might draw out from the hat after the pressing and forming of the same; and this plate is bolted securely to the bar B by screws *c c*, and thereby secured firmly to the bottom

piece, A, with its lower face parallel with the upper face of that piece. Between A and C two side pieces, D D, and front and back pieces, E E, are fitted in such manner as to be capable of sliding toward and from the center of the block. The outer faces of these pieces are so formed that when the said pieces are moved outward as far as permitted the said faces combine with each other and assume a proper relation to A and C to form the flaring portion of the die, the upper part of which is of much larger circumference than the portion A below, and which projects beyond the outer edges of the plate C, the upper surface of which is beveled or rounded off toward the edge in such manner as to make the edge sharp, and to make it combine with the upper surfaces of the pieces D D E E, as shown in Fig. 1, without forming a ridge. The two pieces E E are secured firmly by screws *e e* to two slides, F F, which are fitted to slide toward and from each other on two parallel guide-rods, G G, which are secured by set-screws *g g* to the block B, and the said pieces are made wedge-shaped, as shown at *f f*, to fit between oblique surfaces *i i* on the side pieces, D D, in such manner that when they themselves move outward from the center of the block they also, by their wedge-like action, cause the side pieces, D D, to move outward at the same time. The ends of the slides F F are fitted to mortises in the side pieces D D, and are fitted with pins *d d*, which enter slots *h h* in the said side pieces, the said slots being arranged obliquely and parallel with the surfaces *i i*, upon which the wedge-like action of the pieces E E takes place, the purpose of the said pins being to draw the pieces D D inward or toward each other by their action in the slots *h h* when the pieces E E are drawn inward or toward each other.

H is a double-slotted cam arranged within the bottom piece, A, and secured firmly to a shaft, I, which is fitted to turn in a bearing provided for it in the bar B.

j j are pins secured in and projecting below the slides F F, and entering the slots *k k* in the cam H, in which they are fitted with anti-friction rollers *l l*. The said cam is furnished with a crank-handle, K, by which to turn it by hand in either direction, for the purpose of moving all the pieces D D E E simultaneously

inward or outward, as may be desired, the slots *k* *k* acting through the rollers *ll* and pins *jj* upon the slides *FF*, which carry the front and back pieces, *EE*, and the wedge-faces *ff* and pins *dd*, operating, as before described, upon the side pieces, *DD*.

In setting out the pieces *DD EE* they are stopped in the proper position for their outer surfaces to combine with the outer surfaces of *A* and *C* in such manner as to produce the proper form of the die by the pins *dd*, arriving at the outer ends of the slots *hh*.

Before placing the hat body or the piece of felt-cloth or other material of which the body is to be formed upon the die or block the cam *K* is turned to a position to move the pieces *DD EE* inward far enough to bring them within the outer edges of the plate *C* and bottom piece, *A*, as illustrated in Fig. 2.

In the case of a die to be used in combination with an outer die for pressing and forming the hat-body at one operation, the material of which the body is to be formed is placed over it, and the outer die brought down upon it while in this condition, and after the outer die has been brought down, the cam is turned in a direction to expand or move out the pieces *DD EE* to the condition illustrated in Fig. 1, for the purpose of producing the bell form of the body. After the die has been retained in the above-described position for a sufficient length of time to form the body, the cam is turned in a direction to draw in the pieces *DD EE* in the manner shown in Fig. 2, and by that means the upper or outer die is permitted to be raised and the hat-body to be taken off, neither of which operations could be done while the said pieces set out beyond the piece *A*, which forms

the smaller portion of the body below the bell-shaped portion.

In the case of a block on which hat-bodies are pressed by irons used in the hands, the manipulation of the cam is the same—that is to say, it is first turned to contract or draw in the pieces *DD EE*, and made to hold them in that condition until the hat-body has been put on, after which it is turned in the opposite direction to expand or set out the said pieces, and made to hold them out until the pressing has been finished, when it is turned back again to draw in the said pieces for the purpose of permitting the removal of the hat-body from the block.

We do not claim the manufacture of a hat-block of two or more pieces; but

What we claim as our invention, and desire to secure by Letters Patent, is—

1. The combination of a fixed bottom piece, *A*, a fixed top piece, *C*, and a series of interposed expanding pieces, *DD EE*, the whole constructed and arranged to operate substantially as herein specified, for the purpose set forth.

2. So combining the several expanding pieces *DD EE* with each other and with a cam, *H*, attached to the die or block, that the said pieces may be operated simultaneously, as herein described, to produce the contraction and expansion of the die or block without the removal and reinserion of any portion of the die or block.

R. T. WILDE.
S. H. LYON.
